Inventor
CLIFFORD WILLS

By Richard B. Owen Attorney

UNITED STATES PATENT OFFICE.

CLIFFORD WILLS, OF SALT LICK, KENTUCKY.

RAILWAY SWITCH.

Application filed September 25, 1922. Serial No. 590,463.

To all whom it may concern:

Be it known that I, CLIFFORD WILLS, a citizen of the United States, residing at Salt Lick, in the county of Bath and State 5 of Kentucky, have invented certain new and useful Improvements in Railway Switches, of which the following is a specification.

My invention relates to improvements in railway switches.

10 An object of my invention is to provide a railway switch, which is operated by a mechanism which is mounted on the vehicle which runs on the rails.

15 A further object of my invention is to provide a railway switch, the operating mechanism of which is manually operated by the operator of the vehicle.

20 A still further object of my invention is to provide a railway switch, which is positive in its action.

25 A still further object of my invention is to provide a railway switch, in which the operating mechanism will not interfere with the ordinary control mechanism of a vehicle.

30 A still further object of my invention is to provide a railway switch and an operating mechanism therefor, that is strong, durable, simple and inexpensive in its construction, whereby the number of working parts are reduced to a minimum, and which is well adapted to the use for which it is designed.

35 Other objects and advantages of the invention will be apparent during the course of the following description.

40 In the accompanying drawings forming a part of the specification and in which like numerals are employed to designate like parts throughout the same.

Figure 1 is a top plan view of a railway switch, showing a part of the operating mechanism mounted thereon.

45 Figure 2 is a side elevation of a railway switch, showing a vehicle in dotted lines, and a side elevation of the operating mechanism therefor.

50 Figure 3 is a fragmentary side elevation of a portion of the operating mechanism,

55 Figure 4 is a bottom plan view of a vehicle showing a portion of the operating mechanism for the switch.

Figure 5 is a fragmentary sectional view of a vehicle illustrating a portion of the operating mechanism, and

55 Figure 6 is a section taken on line 6-6

of Figure 5 looking in the direction of the arrow.

Figure 7 is an enlarged top plan view of the track illustrating the cam locking means, 60

Figure 8 is a side elevation of the same, and

Figure 9 is a detail perspective of the cam and cam locking means.

In the drawings, wherein for the purpose of illustration is shown a preferred embodiment of my invention, the numeral 10 represents any well known form of a vehicle such as a street car or a railway train, which runs on a track 11. The track 11 is provided with a switch 12, the track upon which the vehicle is to run being governed by the point 13, that is if the point is in the position as is clearly illustrated in Figure 1, the train will remain on the main track, but if the point is moved the train would follow around the switch 12.

Mounted in any convenient place, within easy reach of the operator of the vehicle is a standard 14 provided with notches 15. A vertical shaft 16 is so mounted upon the front platform of the vehicle, so as to extend a substantial distance above the same and which is provided at one end with an operating lever 17 having a handle 18, said operating lever 17 adapted to engage the notches 15 of the standard 14. The standard 14 is preferably provided with three notches 15, one of which we may term a neutral one and the other two we may term the 90 right and left notches, said operating lever 17 is adapted to be swung either to the right or left so as to engage any one of the three notches and held in said position.

The lower end of the vertical shaft 16 is provided with a semi-circular plate 19 having a downwardly extending pin 20 mounted near the outer extremity thereof, said plate 19 being adapted to swing with the shaft 16.

100 The numeral 21 designates a wheel or roller which is mounted on a vertically extending shaft or link 22 which is adapted to slide within a guide sleeve or lip 23 which is mounted upon the frame of the vehicle. The numeral 24 represents a bell crank which is pivoted upon the frame of the car by means of a bolt 25, and one arm of which is connected to the upper extremity of the link 22 by means of a bolt 26, and the other arm of the bell crank 24 being connected to the link 27 by means of a bolt 28. The

other end of the link 27 is connected to the bell crank 29 by means of a bolt 30, said bell crank being pivoted at point 31, and the other arm of which is connected to a 5 cam 32 by means of a pin 33, said cam plate being provided with a slot 34 which is adapted to receive the pin 20. As the operating mechanism on the right and left side of the vehicle are identical it is only necessary to describe one, as will readily be understood by an inspection of the drawings.

It will thus be seen that by moving the operating lever 17 the shaft 16 will be moved thereby swinging the semi-circular plate 19 which carries the pin 20, which in turn will move the cam 32, thereby rocking the bell crank 29 which will move the link 27, which in turn will rock the bell crank 24 which will move the link 22 upwardly or downwardly depending upon the direction in which the operating lever 17 is moved.

Referring now to the track mechanism, the numeral 35 designates the cam upon which the roller 21 comes in contact. The cam 35 is in the shape of a bell crank, which is pivoted to the rail at 36 by means of a bolt or the like, and the arm 37 of the bell crank 35 is connected to the link 38 by means of a bolt 39. The cam or bell crank 35 is mounted within a housing 40 which is provided with a slot 41 to allow for the movement of the cam 35 therein. A locking member for the cam 42 is pivoted to the rail at 43 and has at one end any form of lock 35 44, and is provided at the opposite end with an outwardly extending flange, which is adapted to engage a boss 46 on the link 38. It will thus be seen, that the outwardly extending flange formed on the pivoted locking member 42, will engage the boss 46 formed on the link 38, and the locking member 44 formed on the opposite end of the locking member 42, will engage the member 35 so as to hold the point in the desired 40 position, until the opposite cam has been struck or operated by the cam operating mechanism, whereby the locking member will be released and the opposite locking member, that is the locking member associated 45 with the opposite cam will be thrown into an operative position. The other end of the link 38 is connected to a bell crank 47 which is pivoted at 48 and the other arm of the bell crank being connected at 49 to a link 50, which carries a pin 51 which is connected to the points 13, said pin 51 being adapted to slide within the slot 52 of the plate 53.

Having set forth the construction and arrangement of the various parts, I will now illustrate the mode of operation of my improved switch, and the operating mechanism therefor. Assume a vehicle such as a street car, is running in the direction of the arrow in Figure 1. As is shown in Figure 1 of the drawings, the point 13 is in such a posi-

tion, that if left unmolested the street car will continue on the main track. Assume now, that the motorman desires to leave the main track 11 and go onto the switch 12. By looking at Figure 6, we find that the 70 right hand wheel 21 is lowered so that it will strike the right hand cam 35, thereby leaving the point 13 in the position as is shown in Figure 1. Now if the motorman desires as above stated, to switch to the 75 switch 12 he would pull the lever 17 into the position as is shown in dotted lines in Figure 6, thereby raising the right hand wheel 21 and lowering the wheel 21 on the left hand side. The left hand wheel 21 will now strike the cam 35 on the left hand side of the track, and through the movement of the link and bell cranks the point 13 will be moved in the direction of the arrow as is shown in Figure 1, and the train will be 80 switched onto the switch 12 as is shown in Figure 1. If the succeeding motorman, that is the motorman of the car behind the one that has gone on the switch desires to move the point in such a manner that he will continue on the main track 11, he merely shifts the lever 17 into the position as is shown in dotted lines in Figure 6, and the point 13 will be moved direct into the position as is 85 shown in Figure 1 of the drawings. 90

We will now go through the detail movement of the various parts when the switch point 13 is moved. The motorman first shifts the lever 17 in the desired position, thereby swinging the shaft 16 which rocks the semi-circular plate 19 which moves the pin 20 in the slot 32, which in turn rocks the cam 32 which is pivoted to the bell crank 29 at 33, said bell crank moving the link 37, which rocks the bell crank 24 which raises or lowers the link 22 which carries the wheel 21, according to which position the lever 17 is arranged. If the wheel 21 is depressed so as to strike the cam or bell crank 35, the link 38 will accordingly be moved through the medium of the bell crank 47, the link 50 will likewise be moved, and the point 13 will be moved in whichever direction, the lever 17 has been set for. It will of course be understood that if the point 13 is in the desired position and the motorman is not required to set the same, the lever 17 will be left in a neutral position. It will readily be seen that this same track mechanism could be utilized to operate a signal, with just as much satisfaction as in moving the point 13, that is a similar mechanism as is disclosed in the drawings, could be so arranged that a train or street car approaching a road-crossing would automatically start an audible or visual signal in operation to warn the approach of the vehicle, although the primary object is the one disclosed in the drawings. 110

It is to be understood that the form of 115

my invention as above shown and described is to be taken as a preferred embodiment of the same, and that various changes in the form, size and arrangement of parts may be 5 sorted to, without departing from the scope of my invention as hereinafter claimed.

Having thus described my invention what I claim as new is:—

1. In combination with a railway switch 10 including a crank, a link connected to said crank, a bell crank pivoted to said switch, one arm of which is connected to said link, a second link running substantially parallel to said track and connected at one end to 15 the other arm of said bell crank, a cam bell crank pivoted to said track, one arm being connected to the other end of the second named link, and means adapted to strike said cam bell crank to operate the point.
2. In combination with a railway switch 20 including a point, point throwing mechanism associated with said switch, including a cam, means mounted on a train to contact with said cam, comprising an operating 25 shaft provided with an operating lever, a semi-circular plate secured to the lower end of said shaft, and being provided with a downwardly extending pin, a cam plate having a slot adapted to receive said 30 downwardly extending pin, a bell crank con-

nected to the end of said cam plate, a link connected to the other end of said cam plate, a second bell crank connected with one arm to said link, and a roller adapted to contact with said point drawing cam, mounted on the 35 other arm of said bell crank.

3. The combination with a point throwing mechanism including a cam, means to lock said cam, and means mounted on a train 40 adapted to contact with said cam.

4. The combination with a point throwing mechanism including a cam, a pivoted locking member associated with said cam, and means mounted on a train adapted to contact with the cam. 45

5. The combination with a point throwing mechanism including a cam, a link connected to said cam, a boss mounted on said link, a pivoted locking member associated with said cam and being provided at one end with an 50 angular extension adapted to contact with said boss, and means mounted on a train adapted to contact with said cam.

In testimony whereof I affix my signature in presence of two witnesses.

CLIFFORD WILLS.
